REFLECTOR SIGNAL

Filed Nov. 11, 1926

UNITED STATES PATENT OFFICE

VICTOR L. OESTNAES, OF WESTFIELD, NEW JERSEY, ASSIGNOR TO AMERICAN GASAC-CUMULATOR COMPANY, OF ELIZABETH, NEW JERSEY, A CORPORATION OF NEW JERSEY

REFLECTOR SIGNAL

Application filed November 11, 1926. Serial No. 147,661.

My invention relates to reflector signals, more particularly to signals adapted for use upon roads, streets and the like and in which central triple reflectors are employed as the reflecting means.

The general object of the invention is to provide an improved and novel construction of means for supporting a group of reflectors firmly and securely in desired fixed cooperative relation with respect to each other.

It also is an object of the invention to provide a novel construction of reflector comprising a group of operatively related reflectors and a diffusing medium in combination with a central element adapted not only to support, but to connect adjoining portions of the reflectors together in a rigid unitary structure.

Another object of the invention is to so combine the said central support with the light diffusing element that said central support operates as a protecting means to protect the said diffusing element against the likelihood of fracture or breakage.

Other objects and advantages of the invention will be pointed out in the detailed description thereof which follows or will be apparent from such description.

In order that the invention may be readily understood and its many practical advantages appreciated reference may be had to the accompanying drawings in which I have illustrated one form of a convenient mechanical embodiment of the same. However, it will be understood that the invention is susceptible of embodiment in various forms of construction within the scope of the claims and without departing from the principle thereof.

In the drawings:

Fig. 1 is a view in which one part of the structure is shown in front elevation, while the other part is shown with a portion broken away in order that parts which otherwise would have been concealed may be exposed;

Fig. 2 is a horizontal transverse sectional view taken on the line 2-2 of Fig. 1;

Fig. 3 is a view in front elevation of the central portion of the signal with the diffusing element removed;

Fig. 4 is a view in sectional elevation taken on the line 4-4 of Fig. 1;

Fig. 5 is a view in front elevation of a radially corrugated washer which acts as a binding or holding member;

Fig. 6 is a view in edge elevation thereof;

Fig. 7 is a view in top plan of the central supporting column or element;

Fig. 8 is a view in side elevation of the upper portion thereof;

Fig. 9 is a view in rear elevation of a portion of the pot or container within which the reflectors are mounted, the said portion being shown for the purpose of illustrating a ventilating means;

Fig. 10 is a vertical section taken on the line 10-10 of Fig. 9; and

Fig. 11 is a view in cross-section of a fragmentary portion of adjoining reflectors indicating the manner in which side flanges 70 on the respective reflectors overlap each other.

In the drawings it will be noted that I have provided a supporting column 1, only a portion of which is shown, upon which the reflector signal is mounted.

The signal comprises a pan-shaped pot or container 2 of metal or other suitable material having flaring sides, as shown. It is provided upon its rear side with an indented 80 or inset portion 3 of arcuate shape in cross-section, as shown, within which a portion of the supporting column 1 is seated. The container may be secured to the post 1 by means of a strap 5, in the manner as is clearly shown 85 in Fig. 2 of the drawings.

The reflector construction as illustrated comprises six hollow central triple reflectors 10. The inner surfaces of these reflectors are light reflecting and the respective reflecting surfaces of each reflector are arranged at right angles to each other. These surfaces have the same relation to each other as the surfaces of one corner of a cube.

These reflectors are arranged in the container 2 radially with respect to the axis thereof. This arrangement is quite clearly shown in Figs. 1 and 2 of the drawings. The upper edge of the outer side (having reference to the reflector structure as shown) of 100

each reflector is provided with a flange 11. These flanges rest upon ledges 12 formed intermediate the top and bottom of the side wall of the container 2. The two other sides; that is the inner sides *a* and *b* of each reflector, meet each other to form a right angle and these two sides terminate at a point, as shown. The several reflectors 10 are arranged about the central axis of the container 2, as indicated in Fig. 1 of the drawings. The corners of the inner ends of each triple reflector are seated in radial downwardly inclined notches 15 formed in the upper end of the supporting column 16. The outer or rear end thereof contacts with the inner surface of the arcuate shaped portion 3 of the container 2, previously referred to. In assembling the reflectors within the container 2 the container is held in flat position with its open side facing upwardly. The column 16 is held in proper position and the reflectors then placed in position with the outer flanges 11 resting upon the ledge 12 and the corners formed by the angular relation of the sides *a* and *b* of each reflector seated within the notches 15. It is convenient that the reflectors be placed in position alternately so that, for instance, when there are six reflectors employed as in the present construction the central radial lines of the three reflectors first placed in position as suggested would be separated from each other by 120°. The presence of these three reflectors in position as stated operates to hold the central support 16 in position while the remaining three reflectors are placed in position and secured together, as will be hereinafter described. The edges of the sides *a* and *b* of the reflectors are provided with outwardly extending flanges 17 which overlap each other, as indicated in the drawings.

The reflectors having been placed in position as suggested it will be noted that the inner ends thereof form in effect a circle about the central axis of the supporting post or column 16. A radial corrugated washer 20 is then placed in position with the corrugations thereof fitting within the angles between the sides *a* and *b* of each reflector 10. Preferably a layer of felt 21 is then placed over the corrugated washer 20. Upon the felt layer a flat metal washer 22 is placed and upon the latter a layer of felt 23 or other suitable material. These various layers of felt and washers are provided with central openings through which a headed screw 25 extends, the inner end of which has screw-threaded engagement with the screw-threaded axial opening 26 in the outer end portion of the post or column 16. Upon tightening the screw 25 it will be apparent that the inner end portions of the reflectors are firmly clamped between the surfaces of the notches 15 and the portions of the corrugations of the corrugated washer 20 which fit within the

angles between the sides *a* and *b* of the respective reflectors. The reflectors are thus rigidly and firmly secured together to form a rigid unitary reflector structure mounted within the container 2.

Preferably a diffusing sheet or element 30 of suitable material is mounted within the outer edge portion of the container 2. The function of the said sheet as a part of a reflector structure is well known and need not be dilated upon herein.

Interposed between the outer edge portion of the reflectors 10 and the container 2 are cushioning strips 31 and 32. The diffusing sheet or element 30 rests upon or against the said cushioning strips. The central portion of the diffusing sheet or element 30 rests against a cushioning block 33 mounted upon the felt layer 23, previously referred to. The yielding character of the cushioning strips 31 and 32 and the block 33 provides a factor of safety to aid in the prevention of breakage or fracturing of the diffusing sheet or element 30 (which usually is of glass).

For the purpose of holding the diffusing sheet or element in position in front of the reflectors 10 I have provided the front edge of the container 2 with a laterally extending flange 35 to which is secured at intervals by screws or otherwise spring clips 36, the inner ends of which are adapted to bear against the outer side of the outer edge portion of the diffusing sheet or element to hold the same against the cushioning strips 31 and 32.

To afford additional protection and to hold the outer edge portions of the diffusing sheet and also to strengthen the structure as a whole I have provided the metal frame 40 which fits over the outer edge of the container and the outer edge of the diffusing sheet or element 30 and is secured to the flange 35 by means of bolts 41 which are provided at intervals, as shown. The inner edge of the frame 40 is provided with an inwardly turned strengthening narrow flange 42, which, however, preferably should not contact with the sheet 30. The outer edge of the said frame (which is of sheet metal) is provided with a rearwardly extending flange 43 which extends over and conceals and protects the joint between the frame 40 and the outer or front edge of the container 2 and also conceals the clips 36 as well as the joint between the container 2 and the diffusing sheet or element 30.

In structures of this character it is desirable that the interior thereof be ventilated, otherwise the reflecting surfaces of the reflectors are liable to become covered with a coating of moisture, whereby their utility as reflecting surfaces is destroyed. For the purpose of effecting ventilation of the interior of the container 2 I have provided the rear or bottom thereof with an opening 45 over which a ventilating hood 46 is secured. This hood is mounted so as to prevent the entry

of water through the opening 45 and at the same time to permit the free passage of air or vapor through the said opening. A screen 47 is held in place over the said opening by means of the said hood, the latter being secured in position by means of screws 48.

In the construction as illustrated embodying my invention I have shown hollow central triple reflectors, but I desire it to be understood that my invention is not limited to reflectors of this particular type or construction and that changes in the details of the construction of the reflecting means may be varied within the scope of the claims without departing from the invention or the principle thereof.

It will be seen that by my invention I have provided means whereby the assembling of the reflectors together in the relation to each other as shown is facilitated and also means whereby the said reflectors may be joined together to constitute a rigid unitary structural effect.

It also will be seen that I have provided a structure in which the inner portions of the reflectors adjoining and surrounding the axis of the signal are bound together and supported by means of a centrally located supporting post or column and also that the said post or column provides means whereby the light diffusing sheet or element 30 may be protected in a way to greatly lessen the percentage of breakage.

Although as illustrated the structure embodying my invention comprises six triple reflectors, yet it will be understood that the number of these reflectors may be decreased or diminished within reasonable limits without departing from the invention or the principle thereof.

Having thus described my invention, what I claim and desire to secure by Letters Patent is:

1. A reflector signal comprising a plurality of reflectors arranged about an axis, means located coincidentally with the said axis and contacting with the rear sides of portions of the said reflectors adjoining the said axis and aiding in the support of the same, and means for rigidly connecting the said reflectors to the first-named means.

2. A reflector signal comprising a container of pan shape, triple reflectors located within said container, the said reflectors being arranged about the central axis of said container and extending radially therefrom, means for retaining the said reflectors within the said container, and means located coincidentally with the said central axis and rigidly connected with the portions of said reflectors adjoining the axis of said container and operating to support the same.

3. A reflector signal comprising, in combination, a container having flaring walls, a post located in axial position with respect

to the said container, the rear inner end thereof contacting with the bottom of said container and the outer end thereof being provided with notches arranged side by side and radially with respect to the axis of the said container, central triple reflectors mounted within the said container intermediate the said post and the walls of the said container, the outer edge portions of the said reflectors being supported upon the said walls and the inner ends thereof fitting within the notches upon the said post or column, means for securing the inner ends of the said reflectors to the said post or column, and means for retaining the said reflectors and the post within the said container.

4. A reflector signal comprising, in combination, a container, a post mounted in the said container axially thereof, one end of the said post resting against the bottom of the said container and the opposite outer end thereof being provided with notches arranged side by side and extending radially, hollow central triple reflectors located within the said container intermediate the said post and the walls of the said container, the outer portions of said reflectors being seated against portions of the walls of the said container and the inner end portions thereof being seated within the radial notches in the said post, means cooperating with the notches of the said post for securing the said reflectors to the said post, and means for retaining the said post and reflectors within the said container.

5. A reflector signal comprising, in combination, a container, a post located within the said container axially thereof with its inner end in contact with the bottom of said container, hollow triple reflectors located within the said container intermediate the said post and the side walls thereof, and means for detachably connecting the inner portions of the said reflectors to the outer end of the said post.

6. A reflector signal comprising, in combination, a container, a post located within the said container axially thereof, the inner end of said post contacting with the bottom of the said container, the outer end of the said post being provided with radially extending notches, hollow triple reflectors located within the said container intermediate the side walls thereof and the said post, the inner ends of the angularly related sides of the said reflectors being seated within the said notches, a corrugated washer mounted over the outer end of the said post or column and overlapping the inner ends of the said reflectors and having its corrugations extended into the angles between the adjoining inner sides of each reflector, means having detachable connection with the said post for clamping the said corrugated washer against the said reflectors to connect the same with

the said post, a block of cushioning material mounted upon the said post outside of the said corrugated washer and outside of the means for securing the latter to the said post, 5 strips of cushioning material located within the container inwardly of the top edge portions of the walls thereof, a light diffusing sheet seated against the said block and strips of cushioning material, and means for retaining the said diffusing sheet and the said post and the said reflectors within the said container, substantially as described.

7. A reflector signal comprising a container having a ventilating opening therein, light reflecting means mounted within the said container and facing outwardly, means for retaining the said light reflecting means within the said container, and means cooperating with the said ventilating opening to prevent 20 the entry of water thereto and at the same time permitting the free passage of air or vapor therethrough.

8. A reflector signal, comprising a container, a reflector mounted therein and supported by a portion thereof, said reflector comprising a plurality of triple reflector units arranged around the axis of said container in contiguous relation to each other and extending radially from said axis, and means 30 extending forwardly from the rear side of said container and being in engagement with portions of the said reflector in adjoining relation to said axis for supporting said reflector against movement inwardly of the 35 said container.

9. A light reflector signal, comprising a container, triple reflectors located in said container arranged around a central axis in contiguous relation to each other, and separate means engaging portions of said reflectors in adjoining relation to said axis for supporting said reflectors in said container.

10. A light reflector signal, comprising a container, a plurality of reflectors located in 45 said container and arranged around a central axis, and separate means engaging portions of two sides of each of said reflectors adjoining said axis for supporting the same in said container.

50 11. A light signal reflector comprising a container, a plurality of reflectors in said container arranged around a central point and having overlapping edges, and means engaging the central front end portions of said edges for supporting said reflectors in the said container against movement toward the bottom thereof.

60 12. A light reflector signal, comprising a container, a reflector mounted in said container, a light-diffusing sheet mounted on said container and supported by portions thereof, means engaging the central portions of said reflector for supporting said central portions, and cushioning means interposed 65 between said last named means and the cen-

tral portion of the rear side of said light-diffusing sheet for aiding in supporting the latter.

13. A light reflector signal, comprising a container, a reflector mounted in said container, a light-diffusing sheet mounted on said container and supported thereby and being located in front of said reflector, a post contacting at its rear end with the bottom of said container and at its front end with the central portion of said reflector, and cushioning means interposed between the front end of said last named means and the said light-diffusing sheet, said cushioning means being in contact with said light-diffusing sheet.

14. A light reflector signal comprising a container, a plurality of reflectors located in said container, a light-diffusing sheet mounted in operative relation to said reflectors, means for engaging the rear sides of portions of the said reflectors, and cushioning means interposed between said last named means and the said light-diffusing sheet for aiding in supporting the latter.

15. A reflector signal comprising a container having a ventilating opening therein, a reflector mounted in said container, and means cooperating with the said ventilating opening to prevent the entry of water thereto yet permitting the passage of air and vapor therethrough.

16. A reflector signal head, comprising a container, reflectors located in said container, a light-diffusing sheet mounted in front of said reflectors, means for securing said diffusing sheet in position, and means for protecting the outer edge portion of said diffusing sheet.

17. A reflector signal head, comprising reflectors and a light-diffusing sheet, a container for receiving said reflectors and diffusing sheet having a flange on its outer edge, means on said flange for securing said reflectors and diffusing sheet in position, and means for protecting the outer edge portion of said diffusing sheet.

18. A reflector signal head, comprising reflectors and a light-diffusing sheet, a container for receiving said reflectors and diffusing sheet and having a flange on its outer edge, means for securing said reflectors and diffusing sheet in position, and means for protecting the outer edge portion of said diffusing sheet.

19. A reflector signal, comprising a plurality of reflectors arranged about an axis, means located coincidentally with the said axis and contacting with the rear sides of portions of the said reflectors adjoining the said axis and aiding in the support of said reflectors, a holding member in engagement with the front sides of the said portions of the said reflectors, and means for connecting 130

the said holding member with the first named means and clamping it against the front sides of said portions to connect the said reflectors to the said first named means.

5 In testimony that I claim the foregoing as my invention, I have hereunto signed my name this 8th day of November, A. D. 1926.

VICTOR L. OESTNAES.
